SAFETY RAZOR

Edward R. Wharton, Medford, Mass.

Application August 19, 1933, Serial No. 685,938

8 Claims. (Cl. 30—12)

My invention relates to safety razors and it has for its object to provide an improved device of this kind.

To this end I have provided a safety razor having the peculiar features of construction and mode of operation set forth in the following description, the several novel features of the invention being separately pointed out and defined in the claims at the close thereof.

10 In the accompanying drawings:

Figure 1 is an enlarged elevation, partly broken away and in section, of a safety razor constructed in accordance with this invention.

15 Figure 2 is a bottom plan view of the guard of the razor shown in Figure 1.

Figure 3 is a side elevation of the upper portion of the razor shown in Figure 1 with the blade of the latter omitted.

20 Figure 4 is a top plan view of the guard shown in Figure 2.

Figure 5 is a plan view of the blade of the razor.

Figure 6 is a section on line 6—6 of Figure 3, but with the blade in position upon the guard.

25 In the illustrated embodiment of my invention 10 is the guard, 11 the handle member of the guard stem, and 12 the blade.

The stem of the guard also includes, as a part thereof, a spindle 13 that is rigidly and permanently connected at its one end with the guard

30 10 so that it extends perpendicularly from the middle of the back side of the latter. The opposite end portion of this spindle is threaded as shown in Figure 1 to receive upon it the 35 tubular interiorly threaded upper end portion of the handle member 11.

The guard 10 is of oblong shape as viewed in plan and is formed with a pair of longitudinal slots 14 which are relatively parallel and spaced 40 apart at opposite sides of the spindle 13. This slotted construction provides the guard with two longitudinal marginal side bars 15 and an intermediate longitudinal median bar 16 with which the spindle 13 is connected.

45 The slots 14 are provided for the reception therein of the elongate hubs of two levers 17, said hubs being pivotally connected with the opposite end walls of the slots of the guard 10 by pintles 18. The hub of each lever 17 is made upon its top side with a longitudinal row of hooks 19 which project beyond the guard and also face outwardly toward the face-engaging sides of said guard.

50 The portion of the hub of each lever 17 between its pintle 18 and the median bar 16 of the

guard is extended laterally away from said pintle and formed to provide an arm or "heel" 20 to cooperate with the inner face of the blade 12 as presently to be described. Also, the hub of each lever 17 is made near its middle with a curved arm 21 disposed alongside of spindle 13 opposite the inner end of handle member 11.

5 The opposite end portions of a coiled spring 22 yieldingly urge the arms 21 outwardly away from each other. This spring surrounds the 10 spindle 13 between handle member 11 and guard 10 and its opposite end portions are formed as hooks which are engaged with the inner sides of arms 21 as shown in Figure 2. Thus, when handle member 11 is rotated on spindle 13 and 15 is moved axially toward or from the guard it acts through arms 21 to effect swinging movements of levers 17 on their pivot pintles 18.

The blade 12, Figs. 1, 5 and 6, is a thin flexible piece of sheet steel that is slightly longer than 20 guard 10 and somewhat narrower, the two opposite longitudinal side marginal portions thereof of having sharpened parallel cutting edges adjacent to and parallel with each of which is a longitudinal row of holes 23. The holes 23 of 25 each row are relatively spaced apart the same as the hooks 19 of either one of the levers 17 and each hole is made of a size and shape to permit the passage therethrough of the head of one of said hooks.

30 When the arms 21, Fig. 1, are at the limit of their outward movement the hooks 19 thereof are positioned so as to register with the holes 23 of the blade and the latter can be placed upon the guard 10 as shown in Fig. 1, with each hook 35 of said levers extending through one of the holes of the blade.

After the blade is placed upon the guard as shown in Fig. 1 the handle member 11 is rotated on spindle 13 in a direction to force said 40 handle member toward guard 10. This axial movement of the handle member acts through the arms 21 to first swing the two rows of hooks outwardly in opposite directions thereby to cause the nose of each hook to overlie the outer marginal portion of the blade immediately adjacent to its hole 23, and then to swing the heels 20 of the levers into engagement with the inner face of the blade. Thereafter, as the inward axial movement of handle member 11 is continued the 45 heel portions 20 of the levers shove the middle portion of the blade 12 away from guard 10 while the opposite side marginal portions thereof are held against outward movement thereby with by the hooks 19 with the result that said 50 55

opposite side marginal portions are swung inwardly toward the guard 10 as shown in Fig. 6. Thus, by axial adjustment of handle member 11 the cutting edges of the blade are adjusted 5 toward and from the guard and positioned relatively thereto as desired for a close shave or for a coarse shave.

It will be clear that this adjustment of the cutting edges toward and from the guard 10 is 10 accomplished by flexing the blade transversely as heretofore, but that in my new razor a pair of blade flexing members are provided on the guard which are operable to apply outward blade-flexing pressure to the inner face of the 15 middle zone of the blade while they hold the opposite side marginal portions of the blade through engagement with the outer face of the latter so that the cutting edges of said side marginal portions are moved toward and from 20 the guard in the opposite sense to that of said middle portion or zone.

The outer sides of the side bars 15 of the guard 10 are curved or rounded away from the cutting edges of the blade 12 and each is formed 25 throughout its length with transverse oblique grooves 24 alternating with transverse oblique ribs 25. These oblique ribs and grooves tend to deflect the razor endwise as it is drawn sidewise over the face of the user thus inducing a shearing stroke while the razor is in motion on the 30 face.

Just inside of the row of ribs and grooves of each side bar 15 the latter is formed upon its 35 top side with a longitudinal channel or trough 26 which serves to catch and hold the lather that is scraped from the face by the blade.

It is an advantage to the above described 40 construction that the blade of the razor is not materially weakened by the holes 23 and that said blade is held and adjustably flexed entirely by the guard structure thus dispensing with the usual blade clamping cap element heretofore provided to engage the outer face of the blade.

It is also an important feature of the above 45 described construction that the absence of the usual blade clamping cap permits the blade 12 to be laid flatwise directly against the face of the user thus avoiding the objectionable scraping action characterizing some of the razors 50 heretofore provided.

Another feature of advantage to the above described construction is that it is unnecessary 55 to disassemble the blade holder when installing or removing the blade as either of these operations are made possible merely by adjustment of the parts of the holder relatively.

When the levers 17 are operated to engage 60 and flex the blade the hooks 19, through engagement with sides of the apertures, serve to 65 adjust the blade into its proper position relatively to the holder.

Each slot 14 is bordered upon its outer side 70 by a straight-edge or shoulder 27 which serves as a stop to limit the approach of the proximate cutting edge to the guard 10 so that it cannot seat on the side bar 15 at the outer side of the adjacent channel 26. These straight-edges or shoulders 27 also co-operate with the hooks to hold the edge portions of the blade 75 straight longitudinally and parallel with the guard.

Experience and investigation have determined 75 the fact that in order to secure the highest degree of safety in combination with satisfactory shaving effects there is a critical relation-

ship necessary to be established between the cutting edge of the razor and the guard and in the present instance this critical relationship exists when the marginal portions of the blade rest against the straight edges 27. The parts will normally occupy this relationship and satisfactory results will be secured in use upon faces of various types or conditions. The setting of the cutting edges at greater distances away from, and out of engagement with, the straight edges 27 will seldom be necessary and only necessary to effect an extremely close shave. In most cases the desired cutting action will be secured with the marginal portions of the blade against the straight edges 27. 15

What I claim is:

1. In a safety razor, the combination with a flexible blade having opposite side cutting edges and formed with apertures adjacent to said opposite side cutting edges, of a holder for said blade comprising a rigid guard provided upon its back side with a handle including a manually adjustable element, and blade-holding mechanism permanently and adjustably mounted on said guard and having parts thereof extending through said apertures, said mechanism being independently adjustable relatively to said guard through adjustment of said element to cause said parts to abut the outer face of said blade adjacent to the apertures thereof when said element is adjusted thereby to apply pressure to the inner face of the middle zone of said blade to flex the latter transversely away from said guard while the cutting edges of said blade are shifted relatively to said guard in the opposite direction. 25

2. In a safety razor, the combination with a flexible blade formed with apertures adjacent to its opposite side cutting edges, of a holder for said blade comprising a guard provided upon its back side with a handle including a manually adjustable element, and blade-holding mechanism permanently mounted on said guard comprising a pair of levers having portions thereof extending through said apertures, said levers being cooperatively associated with said element and operable thereby to first shift said portions laterally into positions to abut the outer face of said blade adjacent to the apertures thereof and thereafter to apply pressure to the inner face of the middle zone of said blade thereby to flex the latter transversely in one direction while the cutting edges of said blade are shifted relatively to said guard in the opposite direction. 50

3. In a safety razor, the combination with a flexible blade formed with apertures adjacent to its opposite side cutting edges, of a holder for said blade comprising a rigid guard provided upon its back side with a handle including a manually adjustable element, and blade-holding mechanism permanently mounted on said guard comprising a pair of levers having hooked extensions projecting through said apertures, said levers being cooperatively associated with said element and operable thereby to first shift said hooked extensions laterally into blade-holding positions opposite the outer face of said blade adjacent to the apertures thereof and thereafter to apply pressure to the inner face of the middle zone of said blade thereby to flex the latter transversely in one direction while the cutting edges of said blade are shifted relatively to said guard in the opposite direction. 65

4. In a safety razor, the combination with a flexible blade having oppositely disposed side 70

5 cutting edges and formed with two straight longitudinal rows of apertures which are parallel with and adjacent to said edges, of a holder for said blade comprising a slotted guard provided upon its back side with a handle including a manually adjustable element, and blade-holding mechanism permanently mounted on said guard comprising a pair of levers each having an elongate hub mounted within a slot of 10 said guard and provided with a straight row of hooked extensions to project through the apertures of one of said rows, said levers being cooperatively associated with said element and operable thereby to first shift said hooked extensions laterally into blade-holding positions 15 opposite the outer face of said blade adjacent to the apertures thereof and thereafter to apply pressure to the inner face of the middle zone of said blade thereby to flex the latter transversely in one direction while the cutting edges of said blade are shifted relatively to said guard in the opposite direction.

20 5. In a safety razor, the combination with a flexible blade having oppositely disposed side cutting edges and formed with two straight longitudinal rows of apertures each of which is parallel with and adjacent to one of said edges, of a holder for said blade comprising a guard provided upon its back side with a centrally disposed perpendicular handle including a manually adjustable element, said guard being formed with two longitudinal slots, one at each side of said handle, and blade-holding mechanism permanently mounted on said guard comprising a pair of levers each having an elongate hub mounted within one of said slots and provided with a straight row of hooks projecting through the apertures of one of said rows and also provided with an arm cooperatively associated with said element, said levers being operable by said element to first shift said hooks laterally into blade-holding positions opposite the outer face of said blade adjacent to the apertures thereof and thereafter to apply pressure to the inner face of the middle zone of said blade thereby to flex the latter transversely in one direction while the side marginal portions of said blade that are outside of said apertures are shifted relatively to said guard in the opposite direction.

25 6. In a safety razor, the combination with a flexible blade having oppositely disposed side cutting edges and formed with two straight longitudinal rows of apertures each of which is parallel with and adjacent to one of said edges, of a holder for said blade comprising a guard provided upon its back side with a centrally disposed perpendicular handle including an axially adjustable element, said guard being formed with two longitudinal slots, one at each side

30 of said handle; blade-holding mechanism permanently mounted on said guard comprising a pair of levers each having an elongate hub pivotally mounted within one of said slots and provided with a straight row of hooks projecting through the apertures of one of said rows and also provided with an arm cooperatively associated with said element, said levers being operable by axial adjustment of said element in one direction to first shift said hooks laterally into blade-holding position opposite the outer face of said blade adjacent to the apertures thereof and thereafter to apply pressure to the inner face of the middle zone of said blade thereby to flex the latter transversely in one direction while the side marginal portions of said blade that are outside of said apertures are shifted relatively to said guard in the opposite direction, and spring means for reversely actuating said levers when said element is shifted axially in the opposite direction.

35 7. A safety razor constructed in accordance with claim 5 wherein said handle includes a threaded spindle connected at its one end with said guard between said slots and wherein said element is an interiorly threaded tubular member mounted on said threaded spindle and cooperatively associated at its one end with said levers.

40 8. In a safety razor, the combination with a flexible blade having oppositely disposed side cutting edges and formed with two straight longitudinal rows of spaced apart apertures each of which is parallel with and adjacent to one of said edges, of a holder for said blade comprising a guard provided upon its back side with a centrally disposed handle including a manually adjustable element, said guard being formed with two longitudinal slots, one at each side of said handle, and blade-holding mechanism permanently mounted on said guard comprising a pair of levers each having an elongate hub pivotally mounted within one of said slots and provided with a straight row of hooks projecting through the apertures of one of said rows and also provided with an eccentrically disposed heel portion, said levers being cooperatively associated with said element and operable by the latter so as to first shift said hooks laterally into blade-holding positions opposite the outer face of said blade adjacent to the apertures thereof and thereafter to force said heel portions against the inner face of the middle zone of said blade thereby to flex the latter transversely in one direction while the side marginal portions of said blade that are outside of said apertures are shifted relatively to said guard in the opposite direction.

45 EDWARD R. WHARTON. 60
